(57) CLAIM

I claim the ornamental design for a combination cigar holder and lighter, as shown and described.

DESCRIPTION

FIG. 1 is a top, front perspective view of a combination cigar holder and lighter showing my new design.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top plan view thereof; and,

FIG. 7 is a bottom plan view thereof.
